J. MILLER

AIR TUNNEL FOR AEROPLANE FUSELAGES

Filed April 9, 1927

Inventor

Joseph Miller,

By *Clarence A. O'Brien*
Attorney

UNITED STATES PATENT OFFICE.

JOSEPH MILLER, OF WALNUT HILL, MAINE.

AIR TUNNEL FOR AEROPLANE FUSELAGES.

Application filed April 9, 1927. Serial No. 182,414.

The present invention relates to an air tunnel to be used in conjunction with an aeroplane fuselage to minimize the head resistance.

5 The important object of the invention lies in the provision of a tube or tunnel extending longitudinally of the fuselage of an aeroplane so as to minimize the head resistance. At the present time, it is quite common to 10 drive aeroplanes by propellers at the front thereof and there is a great resistance set up by the wind created by these propellers hitting the fuselage and it is the prime object of the invention to minimize the effect as 15 far as possible.

Another important object of the invention lies in the provision of a device of this nature having a fan therein operable from the prime mover of the aeroplane.

20 A still further important object of the invention resides in the provision of a device of this nature, which is exceedingly simple in its construction, inexpensive to construct and install, thoroughly efficient and reliable 25 in its operation, and otherwise well adapted for the purpose for which it is designed.

With the above and numerous other objects in view as will appear as the description proceeds, the invention resides in certain 30 novel features of construction, and in the combination and arrangement of parts as will be hereinafter more fully described and claimed.

In the drawing:

35 Figure 1 is a side elevation of an aeroplane fuselage with my improved device associated therewith.

Figure 2 is a front elevation of the device, and

40 Figure 3 is a fragmentary longitudinal section through the forward portion thereof.

Referring to the drawing in detail, it will be seen that 5 denotes an aeroplane fuselage. The numeral 6 denotes a tube or tunnel extended longitudinally of the fuselage, open at the front and rear ends. In the front end of the tube or tunnel 6 there is mounted a pair of spaced internal annular flanges 7. A ring 8 has rollers 9 journaled thereon and 45 ridable in the space between the flanges 7. Turn blades 10 are mounted in the ring 8. A ring gear 11 is secured to the ring 8 by bolts 12, and held spaced from said ring by 50 spacing sleeves 13.

The numeral 14 denotes the prime mover, 55 usually an internal combustion engine, which drives a gear 15, which meshes through a slot 16 with the ring gear 11 and drives the fan blade so as to suck the air through the tunnel or tube and assist in decreasing the head 60 resistance.

It is thought that the construction, utility and advantages of this invention will now be quite apparent to those skilled in this art, without a more detailed description thereof. 65 The present embodiment of the invention has been disclosed in detail merely by way of example, since in actual practice it attains the features of advantage enumerated as desirable in the statement of the invention and 70 the above description.

It will be apparent that changes in the details of construction, and in the combination and arrangement of parts may be resorted to, without departing from the spirit or 75 scope of the invention as hereinafter claimed or sacrificing any of its advantages.

Having thus described my invention, what I claim as new is:

1. In combination, an aeroplane fuselage, 80 a tube extending longitudinally through the aeroplane fuselage and open at both ends, the forward end of the tube being provided with a pair of internal annular spaced flanges, a ring, bearings disposed exteriorly 85 of the ring, means for mounting the bearings on the ring, said bearings being ridable between the flanges, bolts extending from the ring inwardly of the tube, a ring gear supported by said bolts, fan blades extending 90 across the ring, and means for operating the ring gear.

2. In combination, an aeroplane fuselage, a tube extending longitudinally through the aeroplane fuselage and open at both ends, 95 the forward end of the tube being provided with a pair of internal annular spaced flanges, a ring, bearings disposed exteriorly of the ring, means for mounting the bearings on the rings, said bearings being ridable between 100 the flanges, bolts extending from the ring inwardly of the tube, a ring gear supported by said bolts, fan blades extending across the ring, said tube being provided with a slot and a drive gear extending through the slot 105 and meshing with the ring gear.

In testimony whereof I affix my signature.

JOSEPH MILLER.
